DESIGN FOR A HEIGHT GAUGE

Percy Aiken, Minneapolis, Minn.

Application September 29, 1945, Serial No. 123,156

Term of patent 14 years

(Cl. D52—1)

To all whom it may concern:

Be it known that Percy Aiken, a citizen of the United States and resident thereof and of Minneapolis, in the county of Hennepin and State of Minnesota, has invented a certain new, original, and ornamental Design for a Height Gauge, of which the following is a specification, reference being had to the accompanying drawing, forming part thereof.

Figure 1 is a perspective view of a height gauge, showing my new design; and

Fig. 2 is a side elevation of the same.

I claim:

The ornamental design for a height gauge, as shown.

PERCY AIKEN.
